UNITED STATES PATENT OFFICE.

DAVID D. WEISELL, OF FORT WAYNE, INDIANA, ASSIGNOR OF ONE-HALF
TO EDWARD H. RAAB, OF FORT WAYNE, INDIANA.

MAGAZINE TORPEDO-CANE.

SPECIFICATION forming part of Letters Patent No. 738,379, dated September 8, 1903.

Application filed July 27, 1903. Serial No. 167,086. (No model.)

To all whom it may concern:

Be it known that I, DAVID D. WEISELL, a citizen of the United States, residing at Fort Wayne, in the county of Allen, in the State 5 of Indiana, have invented certain new and useful Improvements in Magazine Torpedo-Canes; and I do hereby declare that the following is a full, clear, and exact description of the invention, which will enable others 10 skilled in the art to which it appertains to make and use the same, reference being had to the accompanying drawings, which form part of this specification.

My invention relates to improvements in 15 magazine torpedo-canes.

The object of my present invention is to provide an improved repeating or magazine torpedo-cane economical in construction, safe, efficient, and reliable in operation, and having 20 the magazine for the storage of the torpedoes independent of the cane-body, and thereby avoid the danger incident to an accidental explosion of the contents of the magazine, which sometimes occurs where the 25 magazine is in the cane-body.

My invention consists of a spring-supported magazine telescopically mounted in a mortar and carrying upon its lower end a laterally-movable push-plate adapted in its reciprocation to feed the torpedoes singly from the outlet of the magazine into the firing-chamber of the mortar, and a firing plug or pin adapted to form a contact with the bottom of 35 the mortar and to explode the torpedoes in succession, and a cane-body rigidly but detachably connected to the magazine in alignment with the firing plug.

Similar reference-numerals indicate like parts in the accompanying drawings, in 40 which—

Figure 1 is a vertical central section of the torpedo-magazine, push-plate, and mortar, the latter being taken on the line between the two separable halves of the mortar, showing 45 the operative parts in their normal position with a torpedo in position to be fired and showing the cane-body broken away. Fig. 2 is a view in elevation of the same, with

one side of the mortar broken away and showing the operative parts compressed into the 50 position they assume at the moment of firing. Fig. 3 is a detail side view of the mortar, taken at right angles to Figs. 1 and 2. Fig. 4 is a detail plan of the push-plate or means for feeding the torpedoes singly to the firing-chamber. 55

The mortar is formed of two duplicate castings 1 and 2, rigidly secured together by proper screws 3 at their upper end and by a screw 4, which passes through to the bottom 60 thereof below the firing-chamber. This hollow mortar has a vertical opening in its top, has two opposite sides provided with the longitudinal grooves 5, forming a guideway for the lower end of the vertically-movable magazine 6, and has a vertical guideway 7 for the movable firing plug or pin 8, and whose lower end forms a firing-chamber having a plurality of lateral vents 9, preferably four. The mortar is also provided at its lower end and 65 adjacent to the vents with an anvil or abutment 10, upon which the torpedoes are exploded in the manner hereinafter described. The mortar also has near its upper end the oppositely-arranged shoulders or abutments 70 11 and 12, between which the push-plate is slidably arranged, and has upon one side a 75 torpedo-raceway 13, which intersects the push-plate chamber at its upper end and the guideway 7 at its lower end, Fig. 1.

The magazine 6 is preferably tubular and has its upper portion inclined, as shown, relative to the mortar and to its lower end, which is loosely mounted in the mortar, and provided upon its lower end, as described, with 80 a firing plug, pin, or spike 8. The lower end of the magazine has an inclined transverse slot, in which is loosely mounted a reciprocating push-plate 14, a circular vertical opening 15 therein, and a short groove 16 upon its 85 upper face leading thereto, Figs. 1 and 4. This plate fits snugly between the shoulders or abutments 11 and 12 and is actuated thereby in its longitudinal movement in its containing-slot. 90

The lower tubular portion of the magazine 95

has an annular flange 17, between which and the upper end of the mortar is mounted a retractile coiled spring 18, adapted to normally maintain the operative parts in the relative position they assume in Fig. 1 and against the tension of which the firing-plug is forced down to its anvil 10.

The upper end of the magazine has two tubular branches 19 and 20, the former being in vertical alinement with the mortar and adapted to contain and secure the lower end of the cane-body 21 of any proper dimensions, and the latter being inclined, as shown, and having a magazine-chamber 22 extending from its open upper end to the push-plate and into which the torpedoes 23 are fed at its upper end, which is preferably closed by a flexible rubber cap 24, firmly fixed on the cane-body 21.

20 The operation of my invention thus described is obvious and briefly stated is as follows: When the magazine-chamber 22 is loaded, the push-plate 14 will normally prevent their discharge; but when the magazine 25 is forced down into its lowest limit in the mortar, as shown in Fig. 2, the push-plate 14 will be carried down with it between its inclined abutments 11 and 12 until the opening 15 registers with the lower end of the torpedo-chamber 22, whereupon the adjacent torpedo will by gravity drop into the opening and be retained until by the upward or return movement of the magazine the push-plate will resume its normal position directly 30 above the raceway 13, into which it will descend by gravity to its position upon the anvil 10 in the firing-chamber. The next downward movement of the magazine will fire this torpedo and simultaneously feed another 35 from the torpedo-chamber to the opening 15 in the push-plate, and upon its return will feed this torpedo to the firing-chamber. As the firing-chamber is provided with suitable lateral vents 9 and is very small, the products 40 of the explosion are readily expelled at each discharge. The location of the magazine-chamber is such that the discharge of but a single torpedo can take place at a time, and if by some accidental derangement of the apparatus all the torpedoes in the magazine 45 should explode at once it could not shatter the cane-body, and thereby endanger the hand of the operator, as is often the case where the magazine-chamber is in a tubular cane-body. In such a case the explosion 50 could readily find vent through the open top of the magazine-chamber, as the rubber cap 24 rests loosely and yieldingly thereon. The firing-plug has a lateral recess 25 in one face 55 thereof in register with the opening 15 to aid in the discharge of the torpedoes from the magazine to the raceway 13, and the magazine 6 has an upper-cut recess 26, Fig. 1, in the slot in which the push-plate is mounted

to permit the discharge of torpedoes having 65 a slightly larger diameter than usual.

My invention is thus positive, efficient, and reliable in action, and perfectly safe in use, as the lateral lugs or flanges 27 direct the products of the explosion downward for the 70 protection of bystanders.

Having thus described my invention and the manner of operating the same, what I desire to secure by Letters Patent is—

1. A chambered two-part mortar telescopically mounted on a torpedo-magazine which is freely movable therein, the mortar having a vertical guideway for the lower end of the magazine, an inclined guideway for the feeding push-plate, a firing-chamber and a torpedo-raceway leading thereto; a torpedo-magazine having its lower end provided with an inclined vertically-apertured push-plate transversely mounted therein, and with a firing-plug adapted to enter the firing-chamber, 85 and having a retractile spring mounted thereon adapted to normally maintain the magazine in the uppermost limit of its movement, and having its torpedo-chamber inclined to the cane-body and not in communication therewith; and a cane-body fixed to the magazine as described.

2. A magazine torpedo-cane consisting of a mortar telescopically mounted on the lower end of a magazine freely movable therein; 95 and having guideways for the firing-plug and the feeding push-plate, and provided with a firing-chamber, an anvil in the firing-chamber, and a raceway leading from the push-plate to the firing-chamber; a magazine having a magazine-chamber independent of and disconnected from the cane-body, provided upon its lower end with a firing-plug adapted to enter the firing-chamber, but normally withdrawn therefrom, and having a longitudinally-recessed and vertically-apertured 105 push-plate slidably mounted in a transverse slot therein and adapted to feed the torpedoes to the raceway one at a time.

3. The combination of a chambered mortar having guideways for the firing-plug and the push-plate, and provided with a firing-chamber having an anvil therein and with a raceway leading to the firing-chamber; a magazine telescopically mounted in the mortar and freely movable therein, having a transverse slot for the push-plate and provided with a torpedo-chamber disconnected from the cane-body and open at both ends; a vertically-apertured push-plate slidably mounted in a transverse slot in the magazine, and adapted to alternately register with the torpedo-chamber and the raceway; and a cane-body adapted to be fixed in the magazine at an angle to the torpedo-chamber.

4. In a torpedo-cane a mortar having a firing-chamber and a raceway leading thereto; a magazine telescopically mounted in the

mortar and freely movable therein, having upon its inner end a firing-plug and transversely-movable push-plate provided with a vertical aperture adapted to register alternately with the raceway and the torpedo-chamber, and having in its upper portion an inclined torpedo-chamber, and a cane-body arranged at one side of the torpedo-chamber.

Signed by me at Fort Wayne, Allen county, State of Indiana, this 23d day of July, A. D. 1903.

DAVID D. WEISELL.
